Hamm & Hamm

UNITED STATES PATENT OFFICE.

HOWARD TERHUNE, OF CLEVELAND, OHIO.

BOARD-HAMMER.

1,388,671.

Specification of Letters Patent. Patented Aug. 23, 1921.

Application filed September 1, 1920. Serial No. 407,489.

To all whom it may concern:

Be it known that I, HOWARD TERHUNE, a citizen of the United States, residing in Cleveland, Ohio, have invented certain Improvements in Board-Hammers, of which the following is a specification.

One object of my invention is to improve the construction of a drop hammer of the board type so that the rollers that impinge upon the board will remain true in their bearings under all conditions and will bear evenly upon the board.

A further object of the invention is to construct the driving mechanism for the rollers so that the shaft of each roller will be free to move laterally when wear takes place without interfering with the proper alignment of the rolls in their bearings.

In the accompanying drawings:

20 Figure 1 is a side elevation, partly in section, of a board drop hammer illustrating my invention, the section being on the line 1-1, Fig. 2; and

25 Fig. 2 is a sectional plan view on the line 2-2, Fig. 1, drawn to an enlarged scale.

1 is the base of the hammer on which are mounted the standards 2. Located between the standards is the hammer 3 of the ordinary type to which is attached the board 4. 30 This hammer is adapted to suitable guides in the standard and means is provided for engaging the operating mechanism as the hammer is reciprocated. As my invention relates entirely to the method of mounting the 35 rollers that grip the board, I have omitted all details relating to other portions of the drop hammer.

The two rolls 5, 5 are mounted in bearings 6 and 7. Bearings for each roller are carried by a rocking frame 8. Each frame is eccentrically mounted in bearings 9 of a frame 10 secured to the upper end of the standard 2. Each rocking frame has projecting arms 11, which are connected by pins 12 to heads 13. One of these heads is connected to a fixed rod 14 and the other to a rod 15 actuated, in the present instance, by the hammer. This mechanism forms no part of the present invention.

50 16, 16 are two shafts, each having a belt wheel 17 by which it is driven. Each shaft is mounted in a bearing 18 in its rocking frame and extends through an enlarged opening 19 in one end of the roller 5 and fits

in an opening 20 in the other end of the roller and is secured therein by a key 21. The shaft 16 is reduced at 22 where it extends into the opening 20, forming a shoulder.

By this construction, it will be seen that each roller is free to move toward and from the board 4 on operating the rocking frames 8, and this movement is in no way interfered with by the driving shafts 16 of the rolls, as each shaft is mounted in an independent bearing 18 in its rocking frame and is secured at its inner end to the far end of its roller and passes freely through an opening 19 at the opposite end of the roller so that irrespective of the wear of the bearing 18, due to the pull of the belt, the bearing of the rollers upon the board will not be affected and, consequently, the rollers will bear evenly upon the full width of the board at all times.

I claim:

1. The combination in a board hammer, of standards; a hammer guided in the standards; a board attached to the hammer; two rollers arranged to engage the board and to lift the hammer; bearings at the upper end of the structure; rocking frames mounted eccentrically in the bearings; means for turning the rocking frames; bearings for the rollers mounted in the frames; and a driving shaft for each roller having its bearing in the rocking frame and passing freely through an opening in one end of the roller and attached at its inner end to the opposite end of the roller so that the wear of the shaft in its bearing will not affect the position of the roller in respect to the board.

2. The combination in a board hammer, of a base; two standards mounted on the base; a frame carried by the standards; a hammer adapted to guides in the standards; a board attached to the hammer; two eccentrically mounted rocking frames mounted on the upper frame of the structure on each side of the board; bearings in each rocking frame; a roller mounted in each bearing and arranged to impinge upon the board; a driving shaft for each roller; a bearing on each rocking frame for each shaft; a belt wheel on the outer end of each shaft, each of said shafts extending through an enlarged opening in one end of its roller, the inner end of the shaft neatly fitting an opening in the op-

posite end of the roller; and a key securing the shaft to the roller, the arrangement being such that any wear of the shaft in its bearing will not affect the position of the rollers in respect to the board.

3. The combination in a board hammer, of a hammer; guides therefor; a board at-

tached to the hammer; two rollers arranged to engage the board to lift the hammer; and a driving shaft for each roller so connected thereto as to allow the shaft to move laterally in its bearing without affecting the position of the rollers in respect to the board. ¹⁰

HOWARD TERHUNE.
